United States Patent Office.

STEPHEN R. KIRBY, OF NEW YORK, N. Y.

Letters Patent No. 96,013, dated October 19, 1869.

IMPROVEMENT IN CANAL-TUGS.

The Schedule referred to in these Letters Patent and making part of the same.

To all whom it may concern:

Be it known that I, STEPHEN R. KIRBY, of the city, county, and State of New York, have invented a new and useful Improvement in Canal-Tugs; and I do hereby declare that the following is a full, clear, and exact description of the construction and operation of the same, reference being had to the accompanying drawings, making a part of this specification, in which—

Figure 1 is a longitudinal vertical section.

Figure 2 is a plan view.

This invention relates to tugs used in drawing canal-boats, and for general traction purposes.

The invention consists in providing amidships a slide "towing-chock," capable of moving from one side of the vessel to the other, to which chock the tow-lines are fastened, and from which ropes pass through blocks at the sides to the wheel-house, where they are connected with a winch, to enable the man at the wheel to shift the chock, at pleasure, in, or to regulate the position of the tug, as may be necessary.

In the drawings—

A represents the tug;

a, the well in her stern; and

a', the propeller-wheel.

The holes through the sides of the well are seen at b, running at any desired or practicable angle from forward back, and from outside inward, in order to allow the water to pass in or out the more easily, and having their outer ends provided with parallel bars b', to keep drift-wood or the like from the wheel.

The dimensions of the passages b must be regulated according to the size of the vessel. They should be

as large as may be without weakening the vessel, and as nearly parallel with the keel as possible. They subserve a very important purpose in the way indicated, as must be quite apparent without further description. This is a well-known device.

B is a stationary guide-bar, securely placed athwart the vessel amidships.

To the guide-bar is loosely attached a slide, called a "towing-chock," and to the rear end of the towing-chock is attached the front end of the tow-line c.

From the forward end of the chock, ropes c' c' pass, one to each side of the vessel, and run through blocks d d d along the sides, and thence into the wheel-house C, where they are attached to a winch, by means of which the helmsman is enabled to shift the chock from side to side with the utmost ease, and thus change the position of the tug with reference to keeping it off the sides of the canal, as in passing through a curve, or when the wind blows across.

The chock will be placed as nearly amidships of the vessel as possible, so that she may turn on her centre without difficulty.

Having thus described my invention,

What I claim as new, and desire to secure by Letters Patent, is—

The towing-chock, consisting essentially of the guide B and slide B', in combination with the ropes c' and blocks d, arranged and operating substantially as described.

STEPHEN R. KIRBY.
